Primary Examiner — Manpreet Matharu*Assistant Examiner* — Mojtaba Tehrani*(74) Attorney, Agent, or Firm* — Vorys, Sater, Seymour and Pease LLP(57) **CLAIM**

The ornamental design for a bicycle wheel, as shown and described.

DESCRIPTION

FIG. 1 is a perspective view of a bicycle wheel showing my new design;

FIG. 2 is a front elevational view thereof;

FIG. 3 is a rear elevational view of thereof;

FIG. 4 is a left-side elevational view thereof;

FIG. 5 is a right-side elevational view thereof;

FIG. 6 is a top plan view thereof;

FIG. 7 is a bottom view thereof;

FIG. 8 is a sectional view along line A-A of FIG. 2; and,

FIG. 9 is a perspective view thereof in condition of use.

The design is the overall configuration, shape, ornamentation and pattern of a bicycle wheel as shown in the drawings. In regard to FIGS. 1-8, the broken lines showing elements of the rim and hub are for the purpose of illustration portions of the article and form no part of the claimed design. In regard to FIG. 9, the broken lines in the figure represent unclaimed environment and form no part of the claimed design.

1 Claim, 8 Drawing Sheets(56)
